FLUID-CONTAINING CASSETTE FOR DETERMINING BIOLOGICAL ACTIVITY

John M. Varga, Bayville, N.Y., assignor to Akro-Medic Engineering, Inc., Denville, N.J.

Filed Feb. 6, 1975, Ser. No. 547,456

Term of patent 14 years

Int. Cl. D24—02

U.S. Cl. D32—2 C

FIG. 1

FIG. 2

FIG. 3

FIG. 4

FIG. 1 is a perspective view of a fluid-containing cassette for determining biological activity showing my new design;

FIG. 2 is an end elevation as seen from the left of FIG. 1;

FIG. 3 is a rear elevation thereof; and

FIG. 4 is a top plan view thereof.

I claim:

The ornamental design for a fluid-containing cassette for determining biological activity, as shown.
